UNITED STATES PATENT OFFICE.

CHARLES A. TATUM, OF NEW YORK, N. Y., ASSIGNOR TO WHITALL, TATUM & CO., OF SAME PLACE.

DESIGN FOR A BREAST-PUMP.

SPECIFICATION forming part of Design No. 20,585, dated **March 17, 1891.**

Application filed April 10, 1890. Serial No. 347,404. Term of patent 14 years.

To all whom it may concern:

Be it known that I, CHARLES A. TATUM, a citizen of the United States, residing in the city of New York, in the county and State of New York, have invented and produced a new and original Design for Breast-Pumps, of which the following is a specification, reference being had to the accompanying drawing, forming a part of the same.

10 The drawing illustrates a side view of my design.

This invention relates to a new configuration of breast-pump.

15 The leading features of my design are the trumpet-shaped tube with the enlarged projection on its lower side and the end bulb of substantially spherical shape.

In the drawing, *a* is the cylindrical tube; *b*, the flaring or trumpet-shaped mouth; *c*, the enlargement or bulb on the lower side of ²⁰ the tube, which is longest where it connects with the tube *a*, and *d* the end bulb of substantially spherical shape.

What I claim is—

A design for a breast-pump, the same consisting of the tube *a*, having the trumpet-shaped mouth *b*, the enlargement or bulb *c*, longest where it connects with the tube *a*, and the end bulb *d*, substantially as shown and described.

CHARLES A. TATUM.
